UNITED STATES PATENT OFFICE.

JAMES W. IVORY, OF PHILADELPHIA, PENNSYLVANIA.

TOBACCO-PIPE.

1,386,933.

Specification of Letters Patent.

Patented Aug. 9, 1921.

Application filed April 10, 1920. Serial No. 372,754.

To all whom it may concern:

Be it known that I, JAMES W. IVORY, a subject of the King of Great Britain, residing in the city and county of Philadelphia, State of Pennsylvania, have invented 5 a new and useful Tobacco-Pipe, of which the following is a specification.

My invention consists of a tobacco pipe having in its stem and bowl communicating 10 passages, one of which is open to the exterior of said stem, and the other passage is open to the tobacco receiving chamber of the bowl at the base thereof, and a pin-like device which is adapted to occupy said passages and close the same to the exterior of 15 the stem, and provide a vent around said pin-like device intermediate of the bowl and stem whereby smoke may be drawn from the bowl around said device into the bore of 20 the stem, means being also provided for holding said pin sufficiently tight in position and permitting convenient removal therefrom.

The invention is satisfactorily illustrated 25 in the accompanying drawing, but the important instrumentalities thereof may be varied, and so it is to be understood that the invention is not limited to the specific details shown and described, as long as they 30 are within the spirit or scope of the claims.

Figures 1 and 3 represent longitudinal sections of tobacco pipes embodying my invention.

Fig. 2 represents a transverse section on 35 line 2—2 Fig. 1.

Fig. 4 represents side elevations of forms of pin-like devices with appurtenances that may be employed, different from those shown in Figs. 1 and 2.

Similar numerals of reference indicate 40 corresponding parts in the figures. Referring to the drawings,

1 designates the bowl of a tobacco pipe, and 2 designates the stem thereof, both of 45 which excepting the features of my invention applied thereto, are of usual construction.

In the pipe is a passage 3 which extends partly through said stem from the exterior 50 thereof and partly through the lower portion of the bowl as at 4 when it opens into the tobacco chamber 6 of the pipe, it being noticed that said passage and bore are confluent, and the wall of said passage is 55 cylindrical.

8 designates a closure for the outer ter-

60 minal of the passage whereby smoke is prevented from escaping through said terminal, and smoking is properly occasioned through the stem of the pipe, said closure 65 being of the form of a tapering pin, the point portion of which is at or about the inner terminal of the passage 4 so that the latter owing to its diameter forms a vent 5 around said point portion and thus said 70 vent is in communication with both the chamber 6 of the bowl and the bore 7 of the stem.

It will be noticed also that the tapering stopper tightens against the outer portion 70 of the wall of the passage 3 and so retains its position by contact with the latter. In Fig. 1, the passages 3 and 4 and the closure pin 8 therefor extend at a right angle to the vertical axis of the bowl. In 75 Fig. 3 said passages and pin extend obliquely to said axis.

It will be seen that when the pipe is in use the smoke is drawn from the bowl into the vent 5 around the point portion of the 80 closure pin 8 and from said vent directed into the bore 7 of the stem whereby it may reach the mouth of the smoker.

When the pipe is to be cleansed the closure pin is pulled out from its position and 85 thereby removed from the pipe whereby the passages 4 and 3 are clear from the interior of the bowl to the exterior of the stem, and so nicotin and deposits at the base of the chamber of the bowl and the adjacent 90 portions of the bore of the stem may be removed therefrom through said passages outside of the pipe, thus cleaning the parts of the pipe in question after which the closure pin may be restored to its position 95 in the passages 3 and 4 when the pipe is again in condition for smoking.

The closure is made of such length that the wider end thereof projects beyond the surface of the underside of the stem forming the handle 9 by which said pin may be grasped so as to conveniently manipulate 100 the same for its introduction into the passage 3 and removal therefrom.

In Fig. 4 I show forms of closure pins 105 one having near its point the reduced neck 12, and the other one having in it near its point the opening 13, said opening and neck permitting the passage of smoke and air therethrough from the bowl into the 110 stem.

It will be seen that in order to have the

best results from smoking of my improved pipe, the closure pin 8 has a bearing contact only at the outer rim 10 of the passage whose wall is practically straight from said rim to 5 the wall of the chamber 6 of the bowl. This prevents swelling of said pin which if fitted too closely in position would be likely to occur. I find that it is also advantageous to allow a very small amount of air around the 10 closure pin by loosening the latter, or by the employment of the small vent 14 in the circumference of the pin as shown in Figs. 1 and 3, whereby both air and smoke may be forced out of the passage by breathing into 15 the stem, thus preventing the smoke from lodging and condensing in the passage.

As the tapered end of the closure pin terminates about the chamber 6 of the bowl of the pipe and centrally crosses the bore of the 20 stem, the tobacco is prevented from being drawn into said bore and further hinders the burning tobacco from being disturbed by breathing into the stem as so often is done while smoking to clear the passage. Said 25 pin also allows the excess of smoke and air to distribute the pressure on the tobacco in the bowl. To further assist this a small vent 11 is formed at a suitable place in the bowl from the chamber 6 to the outer wall of the 30 bowl so that a scarcely perceptible issue of smoke is apparent when the smoker breathes into the stem.

Having thus described my invention what I claim as new and desire to secure by Letters Patent, is:—

1. A tobacco pipe having in the lower portion of its stem and the base portion of its bowl communicating passages which are open respectively to the tobacco chamber of 40 the bowl and the exterior surface of the stem, and a tapering pin which is adapted to occupy said passages and form a closure for the latter from the exterior of the stem, the portion of the passage adjacent to the bowl 45 forming around the adjacent portion of the pin a vent by which smoke may be drawn from the bowl into the stem.

2. A tobacco pipe composed of a bowl and stem and having in the latter a passage which 50 bisects the bore of the bowl, and a passage in the base of the bowl continuous of that in said stem, the first named passage being

adapted to be open at the exterior of the stem, and the other named passage being open to the interior of the tobacco chamber 55 of the bowl, and a closure pin adapted to occupy said passage, and to be removably held therein, the end of the pin adjacent to the bowl being of less diameter than the passage that it occupies forming around said end a 60 vent which provides a communication for the draft of the smoke from said chamber into the bore of the stem.

3. A tobacco pipe having in the lower portion of its stem and the base portion of its 65 bowl communicating passages which are open respectively to the tobacco chamber of the bowl and the exterior surface of the stem, and a tapering pin which is adapted to occupy said passages and form a closure for 70 the latter from the exterior of the stem, the portion of the passage adjacent to the bowl forming around the adjacent portion of the pin a vent by which smoke may be drawn from the bowl into the stem, said closure pin 75 being removably held in the passage in the stem.

4. A tobacco pipe having in the lower portion of its stem and the base portion of its 80 bowl communicating passages which are open respectively to the tobacco chamber of the bowl and the exterior surface of the stem, and a tapering pin which is adapted to occupy said passages and form a closure for the 85 latter from the exterior of the stem, the portion of the passage adjacent to the bowl forming around the adjacent portion of the pin a vent by which smoke may be drawn from the bowl into the stem, said closure pin 90 being removably held in the passage in the stem and having an extension exterior of the 95 stem forming a handle for locating the pin in position and removing it therefrom.

5. A tobacco pipe having in its stem and bowl a passage leading from the exterior of the stem to the chamber of the bowl, and a tapering pin which is adapted to occupy said passage and provided in its periphery with a vent for the purpose set forth.

JAMES W. IVORY.
